UNITED STATES PATENT OFFICE.

PETER D. HAY, OF DETROIT, MICHIGAN.

DESIGN FOR A TRAP.

43,145.

Specification for Design.

Patented Oct. 15, 1912.

Application filed August 1, 1912. Serial No. 712,791. Term of patent 7 years.

To all whom it may concern:

Be it known that I, PETER D. HAY, a citizen of the United States of America, residing at Detroit, in the county of Wayne and State of Michigan, have invented a new, original, and ornamental Design for Traps, of which the following is a specification, reference being had therein to the accompanying drawings, forming part thereof.

Figure 1 is a side elevation of a trap showing my new design; Fig. 2, a top end

view of Fig. 1; and Fig. 3 a bottom end view of Fig. 1.

I claim:

The ornamental design for a trap, as shown.

In testimony whereof I affix my signature in presence of two witnesses.

PETER D. HAY.
